(57) **CLAIM**

The ornamental design for a dehumidifier housing, as shown and described.

DESCRIPTION

FIG. 1 is an isometric view of a dehumidifier housing showing our new design.

FIG. 2 is a front view of the dehumidifier housing.

FIG. 3 is a back view of the dehumidifier housing.

FIG. 4 is a left side view of the dehumidifier housing.

FIG. 5 is a right side view of the dehumidifier housing.

FIG. 6 is a top view of the dehumidifier housing; and,

FIG. 7 is a bottom view of the dehumidifier housing.

The features shown in broken lines depict environmental subject matter only and form no part of the claimed design.
